Primary Examiner — Bridget T Eland(74) *Attorney, Agent, or Firm* — Fitch, Even, Tabin & Flannery LLP**CLAIM**

I claim the ornamental design for viscera retainer part, as shown and described.

DESCRIPTION

FIG. 1 is a perspective view of a viscera retainer part showing my new design; and,

FIG. 2 is a top plan view thereof.

The dash broken lines are for the purpose of illustrating environmental structure, while the dot-dash broken lines are used to depict the boundaries of the claimed design; the broken lines for no part of the claimed design.

1 Claim, 1 Drawing Sheet(56)
